[57] CLAIM

The ornamental design for a combined spout and water control handles, substantially as shown and described.

DESCRIPTION

FIG. 1 is a perspective view taken from the top, front and one side of a combined spout and water control handles showing my new design;

FIG. 2 is a rear elevational view thereof;

FIG. 3 is a perspective view taken from the top, front and one side of a modified form of the combined spout and water control handles shown in FIG. 1;

FIG. 4 is a rear elevational view of FIG. 3;

FIG. 5 is a perspective view taken from the top, front and one side of one of the handles shown in FIG. 1;

FIG. 6 is a top plan view of FIG. 5;

FIG. 7 is a side elevational view of FIG. 5;

FIG. 8 is a perspective view taken from the top, front and one side of one of the handles shown in FIG. 3;

FIG. 9 is a top plan view of FIG. 8; and

FIG. 10 is a side elevational view of FIG. 8.

The fragmentary broken line representation of a portion of a lavatory in FIGS. 1 through 4 is for purposes of illustration.
